UNITED STATES PATENT OFFICE.

SAMUEL WILLETT, OF TOTTENHAM, LONDON, ENGLAND.

RAZOR-STROPPING MACHINE.

1,003,021.

Specification of Letters Patent. Patented Sept. 12, 1911.

Application filed February 15, 1910. Serial No. 544,035.

To all whom it may concern:

Be it known that I, SAMUEL WILLETT, subject of the King of Great Britain and Ireland, residing at 124 Broadwater road, 5 Tottenham, county of Middlesex, London, England, manufacturer, have invented certain new and useful Improvements in Razor-Stropping Machines, (for which I have obtained Letters Patent in Great Britain, No. 3,698, dated February 15, 1909,) of which the following is a specification, reference being had to the accompanying drawing.

This invention relates to an improved 15 machine for stropping safety razor blades known as double-edge wafer-blades.

The machine comprises a frame carrying, as usual, a pair of rollers, and midway between which is pivotally mounted, according to my invention, a split spindle to receive an "adapter" or holder, (of special construction as hereinafter fully described) for carrying the razor blade. This spindle is furnished at its inner end with a pinion, 25 and on the inner ends of the rollers are mounted toothed sectors which mesh with the aforesaid pinion, and by means of which a slight vibratory movement is imparted to the razor blade, when the machine is passed to and fro along the strop. Or the split spindle may be interconnected to the said rollers by means of a plate or bar provided at its ends with pins engaging in slots in arms or links mounted fast on the rollers. 30 And in order that my invention may be more clearly understood, I will now describe it fully with reference to the accompanying drawings, wherein:

Figure 1 is a front elevation of my improved stropping machine. Fig. 2 a plan, and Fig. 3 a section on the line $x-x$, of Fig. 1. Fig. 4 shows the "adapter" detached from the split spindle, and Fig. 5 illustrates the said spindle. Fig. 6 is a front elevation, and Fig. 7 a plan, on the line $y-y$, of Fig. 6, illustrating the modified arrangement for vibrating the spindle. Fig. 8 is a section on line 8-8 of Fig. 2; and Fig. 9 is a section on line 9-9 of Fig. 2.

In a suitable frame, constituted by a top plate a , and a bottom plate b , connected together by two rods, c , c , are the rollers c^1 , c^1 , which are mounted on the said rods. Midway between these rollers, and pivotally mounted in the bottom plate b of the frame, 55 is the axis or spindle d , which is split lon-

gitudinally to receive the "adapter" or holder e , carrying the safety razor blade. This spindle d , is furnished with a pinion f , which meshes with two toothed sectors f^1 , f^1 , arranged on opposite sides thereof, and fast on the rollers c^1 , c^1 ; the outermost teeth of each sector being made wider than the intervening teeth, so as to keep the said sectors always in mesh with the pinion f . 60 Normally, the razor blade i lies in the plane of the rollers, and hence the machine can be handled freely without fear of cutting one's self.

The "adapter" or holder e , for the razor blade i , consists of a pair of spring jaws e^1 , between which the blade is clamped. These jaws are, according to the present invention, fixed at one end in a head or button e^2 , formed with a tubular recess or socket e^3 and, when the "adapter" or holder is inserted in the split spindle d , the said tubular recess or socket e^3 , takes over the upper or outer end of the spindle and clamps the jaws of this latter against the "adapter". 70 The head or button e^2 , passes into an opening a^1 , in the top plate a of the frame, and serves as a journal for the spindle d ; this plate being further formed with two other openings a^2 , communicating with the central opening a^1 by slots a^3 , so as to afford a ready passage to the "adapter" and razor blade, and prevent injury to the edges of the latter during insertion into the machine. As shown in Fig. 4, the spring jaws e^1 of the holder e are provided with outer longitudinal projections e^x adapted to engage with the interior of the spindle. 80

According to the modification shown in Figs. 6 and 7, a bar or plate g , is mounted 95 on the split spindle d , and takes the place of the pinion f , the toothed sectors f^1 , f^1 , being replaced by arms or links h , h , provided with slots h^1 , h^1 , into which engage pins g^1 , g^1 , on the ends of the bar or plate 100 g . This arrangement while equally well answering the purpose of that previously described is cheaper to construct.

The razor-blade i having been inserted in the "adapter" e , and this latter clamped within the split spindle d , as above mentioned, stropping of the blade is effected by laying the frame of the machine on the strop and then, by means of the handle j , passing the machine to and fro thereon. The frictional 110 contact between the rollers c^1 , c^1 , and the strop, will cause the former to vibrate and

impart, through the toothed gear, or the links and plate arrangement, as the case may be, a similar movement to the spindle *d*, which will thus present the opposite edges 5 of the blade alternately to the strop. By turning over the machine, and proceeding as before, the stropping of the two edges on the other face of the blade is effected. It is to be thus understood, that, in my construction of stropping machine, the razor blade does not perform a half revolution, but vibrates only to such an extent as to 10 strop first the edge on one side of the blade, and then the edge on the opposite side of the blade, but on the same face.

Having now particularly described and ascertained the nature of my said invention, and in what manner the same is to be performed, I wish it to be understood that I 20 lay no broad claim to the arrangement of the toothed pinion and toothed sectors by themselves, but

I declare that what I claim is;—

1. A machine for stropping safety razor 25 blades comprising a spindle and an

“adapter” or holder comprising spring jaws, between which the razor blade is held, and a tubular head or button, this latter, when the razor blade is inserted in the spindle, operating to clamp the spindle to 30 the “adapter” or holder and also serving as a journal for such spindle.

2. A holder for double edged razor blades, in stropping machines, comprising a rocking spindle, and a pair of spring jaws 35 between which the blade is adapted to be inserted, said spring jaws having at their outer ends a tubular head adapted to inclose the ends of the rocking spindle and to constitute a journal therefor, said jaws being provided with outer longitudinal projections adapted to engage with the interior of the spindle.

In witness whereof I have hereunto set my hand in presence of two witnesses.

SAMUEL WILLETT.
